ORIFICE PLATE CARRIER FOR VALVES

Carl G. Davis, Tulsa, Okla., assignor of one-half
to Joseph A. Coy, Tulsa, Okla.

Application April 18, 1938, Serial No. 202,742

3 Claims. (Cl. 251—68)

The invention relates to orifice plate carriers for valves of a general gate type, usually used in connection with gathering lines leading from gas wells, and discharging into main lines, and has for its object to provide a diagonally split carrier plate for the reception of wafers of the apertured or blank type and co-operating with opposite seats within the body of the valve for positively preventing flow of gas in either direction when the blank wafers are in the carrier, for instance upon breaking of the gathering line. The present practice involves the placing of a wafer on one side of the carrier and packing means on the other, however it has been found that back pressure will by-pass the carrier and packing means.

A further object is to provide a limiting sliding connection between the carrier sections whereby upon dropping of the carrier between the seats, the carrier will be restricted in width by the downward movement of one of the sections thereof and the racks of the other section will engage the operating gears, which gears upon rotation, will expand the carrier and seat the wafers, without a drag on the seats.

A further object is to provide the outer faces of the carrier sections with recesses for receiving and holding orifice plates, blank wafers or rings for measurement purposes or as fillers, according to the desired use.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

40 Figure 1 is a vertical longitudinal sectional view through the device.

Figure 2 is a perspective view of the carrier plate, showing a wafer mounted therein and the racks.

45 Figure 3 is a vertical longitudinal sectional view through a portion of the valve body and through the carrier, showing the combination therewith of an orifice wafer and a filler ring.

Figure 4 is a vertical transverse sectional view 50 through one side of the carrier, showing the slideable connection between the sections.

Figure 5 is a perspective view of the carrier showing the opposite side from the side shown in Figure 2.

55 Figure 6 is a plan view of portions of a piping

system showing the position of use of the device.

The orifice fitting comprises a casing 1 having a removable section 2 secured to the upper side thereof by bolts 2a. The section 2 is provided with a wafer and wafer carrier chamber 3 extending vertically therethrough and which chamber is oblong in horizontal section. Rotatably mounted in the section 2 is a shaft 4, having pinions 5 thereon, which are adapted to mesh with the racks 6 on the carrier section 7 during 10 the lowering or raising of the carriage as a whole. The chambered branch 8 of the fitting 1 has disposed in the chamber 9 thereof a laterally movable member 10, which closes the lower end of the chamber 3 when the carrier is initially 15 placed in the device or when removing the same therefrom. The laterally movable member is provided with a rack 11 engaged by pinions 12 carried by the shaft 13, and by rotating the shaft it will be seen that the member 10 may be 20 laterally moved to operative or inoperative position. Also rotatably mounted in the chamber 9 is a shaft 14 having pinions 15 thereon which are in the same vertical plane as the pinions 5, and are adapted to mesh with the racks 6 when the 25 carrier is moved downwardly by the pinions 5, and to complete the final seating of the carrier. Upon a removal operation the rotation of the pinions 15 will raise the carrier as a unit until the pinions 5 mesh with the rack 6 and the continued rotation of the pinions 5 will continue the upward movement of the carrier so it can be 30 removed from the fitting. The above structure is well known in the art, however the wafer carriers as at present in use are made in one 35 piece and are provided with means on one side only for the reception of wafers.

In the carrier at present in use the opposite side of the carrier from the wafer side is provided with a packing usually of the spring type, 40 and it has been found that this construction drags on the valve seat and under conditions of use does not positively prevent leakage in both directions, which is necessary where the device is used in connection with a gathering line from 45 a gas well to the main line and where there is a breakage in the gathering line between the orifice fitting and the well. Under these conditions a blank wafer, on only one side of the carrier, particularly on the side towards the main line, will not prevent loss of pressure from the main line, through the device and the broken gathering line 16. The main line is designated by the numeral 17.

The orifice fitting is used primarily to deter- 55

mine the volume of gas by differential reading taken from each side of the orifice plate 18 in the carrier, and through a certain size hole at a certain pressure, said hole being designated by the numeral 19. It is computed by Boyles law, thus only so much gas will flow through a given size orifice at a given pressure. The differential reading is registered on a chart, continuously during the entire day.

10 The flow of gas is through the gathering line 16 to the main line 17 and through the orifice fitting in the gathering line. The pressure from the wells is transferred into the gathering line at five hundred pounds and after the gas flows through

15 the orifice fitting it enters the main line 17, which is only carrying four hundred pounds. When there is a break in the gathering line 16 between the orifice fitting and the well, and it is desired to cut the flow through the orifice fitting from

20 the main line, the fitting is turned into a gate valve for preventing the reverse flow from the main line to the broken gathering line. When there is a break in the gathering line, the carrier sections 7 and 7a are provided with blank wafers

25 20, which are received in the channels 21 in the outer faces of the sections 7 and 7a, and they blank the passages 22 through the carrier sections. The carrier sections are provided with contacting diagonal faces 22a, which are in slideable

30 engagement with each other, however the outer faces of the carrier sections are in parallel relation to each other at all positions of the carrier. Carrier section 7 is provided with headed members 23 which are slidably mounted in vertically

35 elongated apertures 24 in the section 7a, consequently the sections have a limited movement in relation to each other. It will be seen that when the carrier, with the wafers carried thereby, is placed into the fitting, the section 7a will drop

40 downwardly by gravity and constrict the width of the carrier as a whole. As the carrier is lowered by the rotation of the pinions 15, the lower end of the carrier section 7a will engage the shoulder 25 below and between the wafer seats 26,

45 and the movement thereof will be arrested, however the downward movement of the section 7 continues with the rotation of the pinions 15 and the bevelled engaging surfaces 22a will cause the sections to be spread apart and the wafers 20

50 to be seated suddenly on the seats 26, therefore it will be seen that there is not a dragging and

wearing action on the seats or wafers. It will also be seen that the pinions 15, in connection with the wedging action between the sections will insure a positive tight seating of the blank wafers, and gas pressure from either side of the carrier will be positively prevented from by-passing the carrier and wafers carried thereby.

When the fitting is in normal use with an orifice wafer 18 carried in one side thereof as shown in Figure 3, a filler ring 27 is used on the opposite side of the carrier. This ring is held in the chambers 21 in the usual manner.

From the above it will be seen that a wafer carrier for orifice fittings is provided which is simple in construction, and one wherein loss of pressure from either side thereof is prevented. It will also be seen that the carrier and wafer will not drag over the wafer seat, but will be seated when the wafers reach their seating position.

The invention having been set forth what is claimed as new and useful is:

1. The combination with an orifice fitting having a fluid passage therethrough, spaced wafer seats in said fitting, an expandable wafer carrier plate within the fitting and extending across the passage between said seats, wafer seats surrounding the passage on opposite sides of the carrier plate, wafers carried by opposite sides of the carrier plate in said wafer seats, said carrier plate being formed from two sections having slideable limited bevelled engagement, stop means in the bottom of the fitting for limiting the downward movement of one of the sections when it reaches seating position and adapted to expand the carrier and means cooperating with the other carrier section for forcing the same to seating position at the end of the closing movement of the other section for seating both wafers.

2. A device as set forth in claim 1 wherein the wafers on opposite sides of the carrier plate are disposed in recesses of the carrier plate and held therein by the seats.

3. A device as set forth in claim 1 wherein the means for limiting the movement of the carrier plate sections in relation to each other comprises headed members carried by one of the carrier plate sections and slidably mounted within the lines of the other section in elongated apertures of the other section.
